Portland, Oreg.

Application March 13, 1951, Serial No. 215,316

7 Claims. (Cl. 235—92)

1

This invention relates to an electrical score board for boxing matches.

The broad objects and general purpose of the invention will be better appreciated when it is realized that boxing is the only spectator sport in which the spectators are given no official knowledge or information on the progress of the fight and the relative standings of the contestants until after the match is finished. The conventional practice of withholding the announcement of the points earned by each contestant frequently produces much discord and dissatisfaction among the spectators, and provokes question as to the soundness of the final official decision, because the spectators, as well as the contestants, have no way of knowing the decisions of the judging officials in each round, as the fight progresses. This is particularly true after a number of close rounds where the officials themselves are not in agreement.

It is, accordingly, the general object of the present invention to provide a score board to indicate, round by round, the number of points awarded to each contestant by each judging official, as well as to indicate the cumulative total of points awarded to each contestant at all times during the fight. A further object is to provide suitable mechanism for indicating and adding up the points awarded to each contestant and to provide mechanism for withholding the indication of the judges' decisions in each round until all the judges have made their decisions, the decisions of all the judges then being indicated simultaneously. It is believed that a score board which will accomplish these results will promote greater interest in and understanding of the sport and will achieve more uniformity and soundness in the decisions of the judging officials. Further objects and advantages will become apparent as the description proceeds in connection with the accompanying drawings illustrating a preferred embodiment of the apparatus, but it is to be understood that various changes may be made in the construction and arrangement of parts, and all such modifications are included in the invention. The invention is not necessarily limited to boxing score boards as certain features may be applied to tallying or scoring for other purposes.

In general, the present score board comprises a plurality of lights for illuminating or forming numbers to indicate the number of the round, the decisions of the officials, round by round, and the cumulative total of points acquired by each contestant. The judging officials are provided with individual scoring boxes having selector

2

knobs to designate the number of points awarded to the contestants. When the official has made his decision, he presses a scoring button on his box, and when all the officials have pressed their scoring buttons, their individual decisions for the round appear simultaneously on the score board. Totalizer mechanisms then go into action to add the points awarded in the new round to the previously earned points of each contestant. An additional control box is provided for the time-keeper, having a push button to change the number of the round and clear the board of the indication of points awarded in the preceding round and a second push button connected with reset mechanism to clear the whole board for a new fight.

In the drawings:

Figure 1 is a view showing the score board and control boxes of a preferred embodiment of the invention; and

Figures 2 and 3 comprise a schematic wiring diagram illustrating the electrical equipment and circuits of the score board and control boxes, the wiring diagram being divided in two parts and Figure 3 constituting a continuation of the same diagram shown in Figure 2.

Referring first to Figure 1, the score board 10 comprises a large panel mounted in a position where it may be viewed by the spectators, and, preferably, also, by the contestants. Ordinarily, two or more of these score boards would be provided for the opposite ends or sides of the arena, so that at least one of the score boards may be viewed easily from any point in the arena. One of these score boards is a master score board containing most of the operating mechanism of the system, and for the purpose of illustration the score board 10 is designated as the master score board. Additional score boards are not shown as they may be connected to the master in an obvious manner. The score board 10 is connected with an electric supply circuit 11 and a plurality of electric cables 12, 13, 14 and 15, leading to the respective control boxes 20 to 23. These control boxes may be disposed at the side of the fighting ring for the use of the usual four officials. Control box 20 is the timekeeper's box, and is equipped with a round step-up push button 24 and a reset switch button 25.

Control boxes 21, 22 and 23 are identical, for the use of the usual three judging officials, and corresponding parts are designated by the same reference numerals. In order to distinguish between the different officials, the box 21 is designated as the referee's scoring box, box 22 as judge No. 1's scoring box, and box 23 as judge No. 2's

scoring box. Each box contains a selector switch 26 which may be turned to different positions to award various numbers of points to "black" or "white," or to a mid point to "E" when the two contestants are adjudged to be even in a particular round. Numeral 27 indicates a switch button which is designated as a scoring button to be pressed by the judging official after he has made his selection on switch 26 in a particular round. Numeral 28 indicates a "selection made" light which is illuminated when the button 27 is pressed to indicate that that official has made his decision.

Referring again to the score board 18, the latter is equipped with a plurality of display sections to display the desired information. Preferably, across the top of the board is a round number display section 30 containing numerals which may be illuminated in sequence to indicate the number of the round. In the center of the board are a referee's decision display section 31, a display section 32 for the decision of judge No. 1, and a display section 33 for the decision of judge No. 2. The display sections 30 to 33 may be formed in different ways, but, in view of the fact that the numbers to be displayed in these sections are never very large, it is preferred to frame each number individually so that the desired number can be illuminated by switching on a lighting unit behind the number or in some equivalent manner. The arrangement is such that the number is inconspicuous when its light is out, whereby selected numbers may be illuminated to indicate the round number and points awarded. The numbers in display sections 31, 32 and 33 correspond to the indicated positions of selector switches 26, the apparatus being adaptable to different boxing rules in different localities.

A feature of the invention, which will presently be explained in greater detail, is that the points awarded in a particular round by the judging officials are not displayed until all three officials have completed their selections independently. Thus, if the referee makes his decision first, he can set his switch 26 accordingly and then press his scoring button 27 which will introduce the information into the electrical system and illuminate the light 28 on his scoring box, but will not produce an immediate indication of his decision on the score board. Assuming judge No. 2 is the next to make his decision, he sets his selector switch 26 and presses his button 27, but his decision does not appear on the judge No. 2 display section 33 on the score board. Then, when judge No. 1 makes his decision, he adjusts his selector switch 26 and presses his scoring button 27. Certain preparatory circuits already having been established by the referee and judge No. 2, the pressing of the third switch button 27 now causes the information transmitted at different times by all three officials to be displayed simultaneously in the three display sections 31, 32 and 33. Thus, the spectators and contestants are apprised of the decision of each official on the round just ended as soon as, but not before, the last official has made his decision on his score box. If the decision of one of the officials is at considerable variance with the decisions of the other two and perhaps quite contrary to the general opinion of the spectators, that fact will be made known immediately, and the judgments of the various officials can be appraised by the spectators as the fight progresses.

The points awarded by each official in a round are preferably allowed to remain displayed in

the display sections 31, 32 and 33 during the following intermission. At the end of each intermission, the timekeeper presses his round step-up switch 24 to extinguish all the lights in these sections. This operation of switch 24 also changes the round number in display section 30.

When the last official makes his decision and the three decisions are displayed, other events also occur in the score board apparatus. At the bottom of the score board 18, there is a display section 34 to indicate the cumulative total of points awarded to one contestant and a display section 35 to indicate the cumulative total of points awarded to the other contestant. The display section 34 comprises a units monogram section 36, a tens monogram section 37, and a hundreds section 38. In order to distinguish the corresponding sections with reference to the two contestants, the units, ten and hundreds sections are designated by numerals 39, 40 and 41 in the display section 35. When the third judging official records his decision by pressing his scoring button 27, the various numbers of points displayed in the display sections 31, 32 and 33 are added in to one or the other, or both, as the case may be, of the cumulative totals in the display sections 34 and 35 by electrical totalizer apparatus which will presently be described in detail. The sections 36, 37, 39 and 40 comprise groups of lights which may be energized in the proper combinations to form digits from zero to 9, as may be selected. Sections 38 and 41 are made to display only the numeral 1, since the number of points awarded to any contestant would never be greater than 199.

Thus, in a close fight, it is readily apparent to the spectators how the variance of opinion of one of the officials in awarding points in some one round can affect the relative standing of the two contestants, and possibly change the final outcome of the fight. An important purpose of the invention is to disclose to the spectators who support the sport any chronic variance of some particular official so that incompetent officials will be revealed and replaced with better officials, to the betterment of the sport. In any event, the final decision cannot come as a surprise to the spectators when they can see how the points are awarded, round by round. The score board will eliminate many misunderstandings between the spectators and the officials and enhance public confidence in competent officials.

Having now described the general features of the score board and the manner in which the scoring is made and displayed, the electrical system for producing the desired indications will be described with reference to Figures 2 and 3. Figures 2 and 3 comprise a single schematic diagram in which the left hand part of the diagram appears on the sheet of Figure 2 and the right hand part on the sheet of Figure 3. The principal components of the system for producing the scoring functions described comprise a plurality of relays, totalizer mechanisms, rotary contact devices and reset solenoids. Where the same elements are duplicated a number of times, all of the duplicated elements are not illustrated. Figures 2 and 3 include only one scoring box, one totalizer unit and one cumulative point display section, the major electrical connections for the missing components being indicated.

Thus, in Figure 2 the numeral 50 designates the referee relay, it being understood that there is also a second similar relay for judge No. 1 and a third similar relay for judge No. 2. Relay 51

is designated as a round step-up relay and relay 52 is designated as a lock relay. Relay 53 is a reset relay, and relay 54 is an alternator relay. The same numerals are used to designate the relays in their entirety and also the solenoid coils thereof.

The points awarded to each contestant in each round are counted at the end of the round by a counting unit 55 which includes a count index solenoid 56, and a motor 57. The various parts of the counting unit are separated in the diagram but may be identified with reference to the common shaft A.

In Figure 3, numeral 60 designates, generally, a round step-up unit actuated by a round step-up solenoid 61 and a round reset solenoid 62. Round number display section 30 is represented by a series of lights bearing the same reference numeral. The lights in the monogram sections 36, 37 and 38 are energized in the proper combinations by a plurality of contact discs mounted on a shaft B in totalizer unit 65. Shaft B is rotated in one direction for scoring purposes by a step-up solenoid 66 and in the reverse direction to clear the board by a reset solenoid 67. Also mounted on the shaft B are units, tens and hundreds cams 71, 72 and 73 for operating a plurality of switches, as shown, the parts being separated for convenience of illustration.

The system is energized from a 110-volt supply 11 having a branch wire 76 in Figure 2 and a branch wire 77 in Figure 3 leading to certain components. Transformer 78 provides reduced voltage for a 50-volt supply circuit 80, a 20-volt supply circuit 81, and a 6-volt supply circuit 82. These different voltages are most suitable for the different types of equipment used in the system, but it is to be understood that a single voltage supply may be used where all the equipment is of the same voltage rating. Transformer 78 is repeated in Figure 3 for convenience in tracing the circuits between the two sheets of drawings. Circuit 80 energizes supply wires 83, 84 and 75 in Figure 2 and supply wires 192, 85 and 250 in Figure 3. Circuit 81 energizes supply wires 100 and 162 in Figure 2 and supply wires 86 and 87 in Figure 3. Circuit 82 energizes supply wires 88 and 89 in Figure 3.

Referee relay 50 is energized by a pair of wires 90 and 91. Wire 90 connects with supply wire 83 through a normally closed switch 92 on reset relay 53, the other contact of switch 92 being connected to wire 93. Wire 91 is connected to wire 94 leading to one terminal of switch 21 on the referee's box 21. The other terminal of switch 21 connects through wire 95 to supply wire 84. Wire portions 90a and 90b connect with the relays for the other two judging officials, not shown, corresponding with relay 50.

The lights in the referee's display section 31 in Figure 1 are also designated by the same numeral 31 in Figure 2 for convenience of identification. Selector switch 26 has two mutually insulated switch arms 96 and 97. Switch arm 96 is connected to a wire 98 and the series of contacts 99 engaged by this switch arm are connected directly to the lights 31. The other terminals of lights 31 are connected to supply wire 100. Wire 98 is connected with one arm of a normally open switch 101 on lock relay 52, the other arm of this switch being connected with supply wire 102. Wire portions 98a and 98b, and 100a and 100b, supply the other two scoring boxes which are not included in Figure 2. Wire portions 102a and 102b supply the indi-

cator lights 28 on the other two scoring boxes. Similarly, wire portions 76a and 76b connect with the switch arms 97 on the other two scoring boxes.

One terminal of light 28 on the scoring box is connected with supply wire 102 and the other terminal is connected with a wire 106 leading to one arm of a normally open switch 107 on the referee relay 50. The other arm of switch 107 is connected with a wire 103 leading to supply wire 100.

One terminal of lock relay solenoid 52 is connected directly to supply wire 83 and the other terminal is connected to a wire 110 leading to one arm of a normally open switch 111 on the referee relay 50. The other arm of this switch is connected with supply wire 84 through two switches 111a, 111b, in series. The judge No. 1 and No. 2 control boxes, not included in the wiring diagram, are connected with two relays, not shown, which are similar to the referee relay 50 and include the switches 111a and 111b, corresponding to the switch 111.

The referee's relay 50 also includes a normally open switch 112 having one switch arm connected with wire 94 and the other switch arm connected with a wire 113. Lock relay 52 includes a second normally open switch 115 having one switch arm connected directly with supply wire 84 and a second switch arm connected with a wire 116.

The solenoid of round step-up relay 51 has one terminal connected directly to supply wire 83 and its other terminal connected with a wire 117 leading to round step-up switch 24 in time-keeper's box 20. This relay includes a normally closed switch 118 and a normally open switch 119. One arm of switch 118 is connected with wire 113 and the other arm is connected to supply wire 83. One arm of switch 119 is connected with supply wire 84 and the other arm is connected with a wire 120 which continues on to Figure 3.

The solenoid of reset relay 53 has one terminal connected to supply wire 83 and its other terminal connected to the two wires 121 and 122, the latter connecting with one of three terminals in timekeeper's reset switch 25. Relay 53 has a normally closed switch 92 and three normally open switches 126, 127 and 128. One arm of switch 126 is connected with wire 93 and the other arm is connected with a wire 129. One arm of switch 127 is connected to wire 121 and the other arm is connected to a wire 125 leading to Figure 3. One arm of switch 128 is connected to a branch supply wire 130 and the other arm is connected to wire 131.

The solenoid of alternator relay 54 has one terminal connected to supply wire 83 and its other terminal connected to the two wires 131 and 132. This relay has two normally closed switches 133 and 134, and two normally open switches 135 and 136. One arm of switch 135 is connected to wire 116 and the other arm is connected to wire 131. One arm of switch 133 is connected to wire 116 and the other arm is connected to wire 137. The two switches 134 and 136 have a common central arm connected with wire 151. This arm normally makes contact with a top arm connected with a wire 138 when the solenoid is deenergized. Wire 133 continues on to the totalizer unit in Figure 3. When the solenoid is energized, this central switch arm makes contact with a bottom arm connected with

wire 140 which continues on to the other totalizer unit, not shown.

Motor 57 drives a shaft A carrying a pair of insulated switch arms 144 and 145, a count index disc 146, and a reset cam 147. Switch arm 144 engages only with a pair of stationary contacts 148 and 149 connected with the wires 95 and 132, respectively.

Switch arm 145 is connected with wire 151 and wipes a circle of contacts designated generally by the numeral 150. The contacts in this circle are spaced apart a distance greater than the width of the switch arm so that the circuit through wire 151 is interrupted as the arm moves from one contact to the next. The spaces between the contacts to be energized may be fitted with an equal number of dead contacts (not shown) to make the switch arm ride smoothly around the circle. The single contacts 152 and 153 are connected to the respective contacts in the series 154 under the switch arm 97 corresponding to the first black and white positions, respectively, of the selector switch knob 26 as shown in Figure 1. The circle of contacts 154 has a central dead contact 155 which is not connected with any of the contacts in the circle 150. Switch arm 97 rests on the dead contact 155 when the selector knob 26 is in the "even" position giving no points to either contestant.

Numerals 156 and 157 designate groups of two interconnected contacts connected with respective single contacts in the contact circle 154 corresponding to the two different two-point positions of the switch knob 26. Similarly, the reference numerals 158 and 159 designate groups of three interconnected contacts, and numerals 160 and 161 designate groups of four interconnected contacts, each group being connected to one of the contacts in the circle 154 having a corresponding point value for one of the contestants. The arrangement is such that when the selector knob 26 is placed in its "E" position, switch arm 97 rests on dead contact 155 and the circuit through wire 151 is not energized when switch arm 145 driven by motor 57 passes over the circle of contacts 150. However, if switch arm 97 rests on one of the other contacts in the circle of contacts 154, a certain number of contacts in the circle 150 will thus be energized, causing the circuit 151 to be energized momentarily a corresponding number of times in quick succession when the arm 145 sweeps around the circle of contacts 150. The remaining portions of the circle of contacts 150, not shown connected in Figure 2, are, in practice, connected in a similar manner to the scoring boxes 22 and 23 of the two judges, not shown in Figure 2. Thus, it is apparent that twenty contacts are necessary for each scoring box, making a total of sixty active contacts in the circle 150.

The contacts in circle 150 which are energized by the three selector switch knobs 26 transmit pulse signals to the totalizer units when switch arm 145 makes a complete revolution, counting up the points awarded by all the judging officials. Means will presently be described for separating the count for one contestant from the other count.

One terminal of count motor 57 is connected to a wire 170 leading to the supply wire 84, and the other terminal is connected to the two wires 129 and 171. Wire 171 leads to one arm of a switch 172 which has its other arm connected with supply wire 83. Count index disc 146 is provided with a notch 173 which is normally engaged by a lever 174 connected with the armature

175 of solenoid 56. One terminal of this solenoid is connected with wire 137, and the other terminal is connected with a wire 176 leading to supply wire 83. When solenoid 56 is energized, armature 175 is drawn into the solenoid to close the switch 172 and withdraw lever 174 from the notch 173 to release the count disc 146 for rotation.

Reset cam 147 cooperates with a switch 177 to close and open this switch repeatedly as shaft A revolves. This cam is positively connected to shaft A to revolve whenever the motor is operated, but switch arms 144, 145 and disc 146 are driven by a friction clutch 146' and are held against rotation by lever 174 when the motor is operated for reset.

One arm of switch 177 is connected with wire 131, and the other arm is connected with a wire 178 having two branches 179 and 180 connecting with the two reset solenoids which remove the monogram numbers from the two display sections 34 and 35 at the end of the fight. The wire 180 continues on to Figure 3 where it is connected with reset solenoid 67. Wire 179 connects with the rest solenoid in the other totalizer, not shown.

Referring now more particularly to Figure 3, the display section 30 comprises a plurality of lights for indicating the number of the round, each light having one terminal connected with supply wire 87 and its other terminal connected with one of a series of contacts 185 arranged in a semi-circle in the round step-up unit 60. The series of contacts 185 is swept by a switch arm 186 connected with a ratchet wheel 187.

Ratchet wheel 187 is held in indexed positions 35 with switch arm 186 resting on one of the series of contacts 185, by means of an indexing lever 188. Indexing lever 188 is connected with an armature 189 in round reset solenoid 62 to release the ratchet wheel for rotation when the solenoid is energized. This lever and armature are normally urged toward indexing position by spring action. Ratchet wheel 187 is also engaged by a step-up pawl 190 connected with an armature 191 in round step-up solenoid 61. The ratchet wheel is spring returned in one direction and magnetically advanced in the opposite direction one step by each stroke of the armature 191.

One terminal of solenoid 61 is connected with wire 120, and the other terminal is connected with supply wire 192. One terminal of round reset solenoid 62 is connected with supply wire 192, and the other terminal is connected with wire 193 which continues on from referee's push button switch 25 in Figure 2 to one arm of a switch 195. Switch 195 is normally held open by the spring action of armature 189 and is released to closed position when this armature is drawn into the solenoid 62 to release the ratchet wheel 187. The other arm of switch 195 is connected to a wire 196 leading to one arm of a switch 197, the other arm of the latter switch being connected with supply wire 85.

Switch 197 is normally closed, but one of the switch arms is elongated at 198 to project into the path of a pin 199 which is rotatable with switch arm 196. Pin 199 engages the arm 198 to open the switch 197 when the switch arm 196 reaches its zero position extinguishing all the lights in the display section 30.

The units, tens and hundreds display sections 36, 37, and 38 in Figure 1 are controlled by totalizing unit 65 shown in Figure 3, and the other monogram sections 39, 40, and 41 are controlled by a second similar totalizing unit not shown. For convenience of illustration in the

schematic diagram the totalizing unit 65 has been dismembered to show the individual contact arms of the switches associated with the three cams 71, 72, and 73 on the shaft B. The units cam 71 and twenty-four contact discs for the twenty-four lights in the units section 36 are keyed to the shaft B. The position of cam 71 is indicated in phantom on shaft B. The tens cam 72 and twenty-four contact discs for the twenty-four lights in tens section 37 are fixed on a sleeve 211 which is rotatable on the shaft B, the position of cam 72 being indicated again in phantom. The hundreds cam 73, indicated in phantom, and a single contact disc 201 are mounted on a second sleeve 200 on the shaft to cooperate with a contact finger 202 to turn the six lights in hundreds section 38 on and off.

Step-up solenoid 66 has an armature 205 equipped with a pawl to advance ratchet wheel 206, keyed on shaft B, step by step in one direction. Reset solenoid 67 has an armature 200 equipped with a pawl to rotate a similar but reversed ratchet wheel 261 step by step in the opposite direction to clear the board. These solenoids are connected with the common supply wire 77 which has a branch 77a for the corresponding solenoids in the other totalizer unit, not shown.

Shaft B carries a one tooth gear 207 to rotate a ten tooth gear 208 one tooth in each revolution of shaft B. Gear 208 is integrally connected with a second gear 209 in driving engagement with a gear 210 on sleeve 211 which carries the tens cam 72 and the contact discs for the twenty-four lights 37. A few of the units contact discs are shown on the shaft B designated by the numeral 212 and a few of the tens contact discs on the sleeve 211 are indicated by the numeral 213.

Sleeve 211 carries a one-tooth gear 215 which is arranged to advance a ten tooth gear 216 one tooth in each revolution of the sleeve. Gear 216 is integrally connected with a second gear 217 in driving relation with a gear 218 which rotates the sleeve 200 carrying hundreds cam 73 and contact disc 201. There is a stationary contact finger for each contact disc as indicated at 221 and 222, it being understood that there are twenty-four such contact fingers connected with the individual lights in section 36 and twenty-four contact fingers connected with the lights in section 37. These discs carry contacts appropriately arranged to energize the lights in different patterns to form the different numbers in sequence whereby the three monogram sections will count from 1 to 199 if the step-up solenoid 66 is energized 199 times. As units shaft rotates from its "nine" position to its "zero" position the one tooth gear 207 effects rotation of sleeve 211 to its next position as from 0 to 1, 1 to 2, etc. The one tooth gear 215 functions in a similar manner to complete the number 100 upon the next operation of step-up solenoid 66 after the number 99.

To make the circuits through the monogram lights, the supply wire 89 is grounded on the frame 65' of the totalizing unit 65, and the contacts on the insulating discs 212 and 213 are all electrically grounded to this frame. Thus, the circuits to the individual lights are completed through wires such as the wire 230 leading from the finger 221. Wire portion 89a is grounded on the frame of the other totalizer unit, not shown.

All the lights in the units section 36 have one terminal connected to a common wire 231, and

all the lights in the tens and hundreds sections 37 and 38 have one terminal connected to a common wire 232. The three cams 71, 72 and 73 are provided with notches 235 for operating three sets of switches. Switches 240, 241, and 242 are all normally open switches in the zero position of shaft B, and these switches are closed simultaneously by movement of the notch 235 whenever the shaft B rotates out of its zero position. The switches 243, 244, and 245 operate in a similar manner under the control of cam 72. Similarly again the two switches 246 and 247 are closed by movement of the hundreds cam 73 out of its zero position. Switches 240 and 241 are adapted when closed to connect wire 88 to both of wires 231 and 232. Wire portion 88a is similarly connected with the other totalizing unit, not shown. Switches 243 and 244 perform the same function. Switch 246 when closed connects wire 88 with wire 231 only. Switches 242, 245 and 247 all serve to connect wire 122 with supply wire 250.

Operation

Assuming that the board has been cleared and the fight is ready to start, the timekeeper presses his round step-up switch button 24 on his time-keeper's box 29. This completes a circuit through wire 75, switch 24 and wire 117 to energize round step-up relay 51, momentarily opening switch 118 and closing switch 119. The opening of switch 118 at this time has no effect. The closing of switch 119 makes a circuit from supply wire 84 through switch 119, wire 120, round step-up solenoid 61, and back to supply wire 192, to produce a single stroke of armature 191, actuating ratchet wheel 187 clockwise and moving contact arm 186 to its first position, energizing the first light in the display section 30 to indicate round 1. Relay 51 and solenoid 61 immediately return to their original positions as soon as push button switch 24 is released, the ratchet wheel 187 and switch arm 186 remaining, however, in their No. 1 position by the retaining action of the spring biased indexing lever 188 which permits the ratchet wheel to be advanced clockwise but prevents it from returning counterclockwise from its advanced positions.

After the first round has ended, the referee and judges award points to the contestants according to the scoring system in use by turning the knobs 26 on their respective control boxes 21, 22 and 23. The mere setting of these switch knobs has no immediate effect on the system. After making his selection, each official presses his push button 27. Let it be assumed that the referee having the control box 21 is the first to make his selection and press his control button 27. The closing of this switch completes a circuit from supply wire 86, wire 95, switch 27, wire 94, wire 91, referee relay 50, wire 90, and normally closed switch 92 back to supply wire 83. The energization of relay 50 closes the three normally open switches 107, 111 and 112.

Switch 107 completes a circuit through wires 103, 106 and 102 to energize the "decision made" indicating light 28 on the referee's box. Switch 112 establishes a holding circuit for solenoid coil 50 through wire 93, normally closed switch 92, wire 90, wire 91, wire 94, switch 112, wire 113, and normally closed switch 118 back to supply wire 83, whereby release of push button 27 does not cause the relay 50 to reopen. Switch 111 is one of three switches in series with the solenoid winding of lock relay 52, the other switches being

11a and 11b on judge No. 1 relay and judge No. 2 relay, respectively, which relays are not shown. When all three officials have made their selections on their respective scoring boxes 21, 22 and 23, and pressed their push button switches 27, the other two relays will be actuated in the manner of relay 50 to close all three of the switches 111, 111a and 111b, thereby energizing the solenoid coil of lock relay 52. Thus, lock relay 52 is likewise maintained energized after the release of push button switches 27.

The actuation of lock relay 52 closes normally open switches 101 and 115. Switch 101 completes a circuit from supply wire 84 through wire 98, switch arm 96, and one of the lights 31 corresponding to the selection of the referee. Similarly, one of the lights 32 is energized through a parallel circuit between wires 98a and 108a controlled by scoring box 22, and one of the lights 33 is energized by a parallel circuit through wires 98b and 108b controlled by scoring box 23.

The closing of switch 115 establishes a circuit from supply wire 84 through switch 115, wire 116, normally closed switch 133, wire 137, count index solenoid 56, and wire 176 to supply wire 83. The energization of solenoid 56 withdraws the index arm 174 from engagement with disc 146 and simultaneously closes switch 172 to energize count motor 57 through wires 170, 171 and switch 172. Shaft A then rotates disc 146, switch arms 144 and 145, and cam 147. The operation of switch 177 by cam 147 at this time has no effect because of the normally open switch 128 in series circuit therewith.

As switch arm 145 sweeps the circle of contacts 150, it encounters, in succession, groups of contacts energized according to the positions of switch arms 97 in the three control boxes 21, 22 and 23. When switch arm 145 reaches such a group of energized contacts, the circuit through the switch arm is interrupted between contacts as the arm passes from one to the next to produce a series of electrical impulses in the circuit. The circuit thus controlled includes supply wire 76, switch arm 97, one of the contacts 154, and one of the groups of contacts 152 to 161, energized by the selection made on control box 21. Similarly, other groups of contacts in the contact circle 150 are energized by the other two control boxes depending upon the selections made. Whenever the selection is "E," no contacts in the circle 150 are energized because, as illustrated in the case of switch arm 97, no circuit is connected with the dead center contact 155.

All the contacts for scoring points for one contestant are located on one side of the circle 150, and all the contacts for scoring points for the other contestant are located on the remaining half of the circle 150. Thus, as switch arm 145 rotates through its first half revolution, the total number of points awarded by all three officials to one contestant are represented in the first half of circle 150 as energized contacts which produce a corresponding number of electrical impulses in wire 151 which is then connected through normally closed switch 134 with wire 138 leading to the step-up solenoid 66 in the totalizer unit 65 in Figure 3. This solenoid circuit is completed back to the source of supply through wire 77. The armature of solenoid 66 is thereby actuated in succession a number of strokes equal to the total number of points awarded to the one contestant by all three officials in the first round. Ratchet wheel 206 and shaft B are stepped up

accordingly, establishing the proper circuits through units contact discs 212 and fingers 221 to energize the proper lights in units section 36 to form the desired number. As soon as this number exceeds nine, gears 208, 209 and 210 are operated by the single tooth gear 207 to rotate sleeve 211 one step and form a numeral 1 in the tens section 37.

When switch arm 145 has rotated 180 degrees from its starting point, the totalizing of the points for the one contestant is completed and contact arm 144 then makes engagement with stationary contacts 148 and 149. A circuit is thereby completed from supply wire 84 through switch arm 144 to wire 132 and thence through the solenoid of alternator relay 54 back to supply wire 83. This operation opens switch 134 and closes switch 136 to transfer the pulse signal from wire 138 to wire 140 as switch arm 145 moves around the remainder of the circle of contacts 150. Wire 140 is connected to the step-up solenoid of the other totalizer unit, not shown, and the totalizing operation is then carried out on the monogram sections 39, 40 and 41 for the other contestant.

The actuation of alternator relay 54 also opens switch 133 to open the circuit of count index solenoid 56 and release index arm 174 to engage notch 173 at the end of 360 degrees of rotation. Armature 175 cannot move sufficiently to open motor switch 172 until notch 173 presents itself under the index lever 174, and then the motor is deenergized and the disc 146 and contact arms 144 and 145 indexed in starting position. Switch 135 provides a holding circuit for alternator relay solenoid 54 through wires 131, switch 135, wire 116 and closed switch 115 back to supply wire 84, after the switch arm 144 has passed the contacts 148 and 149.

When round step-up switch button 24 is pressed again, round step-up solenoid 61 is energized, as previously, to advance switch arm 186 one step and illuminate the next round number in display section 30. The actuation of round step-up relay 51 opens switch 118, thereby interrupting the previously described holding circuit for referee relay solenoid 50 through switch 118. When relay 50 is thus deenergized, the opening of switch 111 deenergizes lock relay 52 which extinguishes all the lights in display sections 31, 32 and 33 by opening switch 101 in the circuit of wire 98. The cumulative monogram display sections 34 and 35 are not disturbed and remain illuminated.

In succeeding rounds the same operations are repeated, with the totalizer units adding in the new points for each contestant in each round to show the accumulated totals of points at all times in the display sections 34 and 35.

The first actuation of step-up solenoid 66 turns units cam 71 into switch closing position, closing the switches 240, 241 and 242. The closing of switch 240 energizes wire 231 from supply wire 88, wire 231 being a common terminal or bus bar for the twenty-four lights in the units section 36. Similarly, the closing of switch 241 energizes wire 232 which is a common terminal for the remaining lights. The closing of switch 242 connects supply wire 250 with wire 125. This has no effect on the system at this time in view of the open switch 127 in this circuit. The switches operated by cams 72 and 73 are in parallel with the switches just mentioned, and establish parallel circuits to prevent deenergization of active cir-

cuits when units cam 71 passes its zero position at cumulative totals of 10, 20, 30, etc.

At the end of the fight, the whole board is cleared by merely pressing the timekeeper's reset switch button 25. This action closes two circuits, one through wire 193 and another through wire 122. The circuit through wire 193 energizes round reset solenoid 62, drawing in its armature 189, closing normally open switch 195 and releasing index lever 193 from pawl wheel 187. Ratchet wheel 187 and switch arm 186 are spring returned counter-clockwise to starting or zero position, thereby extinguishing all the lights 30. If desired, the spring return mechanism may be arranged to return arm 186 to its round one position instead of a zero position. In return movement, the teeth of ratchet wheel 187 freely pass actuating lever 190. The closing of switch 195 establishes a holding circuit for solenoid 62 through wire 196 and normally closed switch 197 after push button 25 is released, to insure that indexing lever 188 will be held withdrawn until the ratchet wheel 187 and switch arm 186 reach their zero position. When these parts reach zero position, pin 199 engages arm extension 198 to open switch 197 and deenergize solenoid 62. The round step-up unit is thus restored to its initial condition.

The circuit established by reset switch 25 through wire 122 energizes the solenoid of reset relay 53 to return both totalizer units to zero position. When the monogram lights show a total of ten points or more, both of switches 242 and 245 will be closed, holding a circuit from wire 250 through wire 125 and switch 127 to the solenoid of reset relay 53. The closing of relay 53 opens switch 92 and closes switches 126, 127 and 128. The opening of switch 92 deenergizes referee relay 50, and also the two judge relays (not shown) by reason of similar connections. This operation, by reason of opening switch 111, deenergizes lock relay 52 and extinguishes the lights in sections 31, 32 and 33 by the opening of these light circuits at switch 101.

The opening of switch 115 interrupts the holding circuit of alternator relay 54 through wires 116, closed switch 135 and wire 131, allowing this relay to resume its deenergized position illustrated.

The closing of switch 126 establishes a circuit through wire 93, switch 126, wire 129 and motor 57 to turn reset cam 147. Switch arms 144 and 145 are held stationary by the engagement of index arm 174 in the notch 173 of disc 146, the friction clutch 146 slipping to allow rotation of shaft A. The rotation of cam 147 closes and opens switch 177 in quick succession, producing a pulse signal in a circuit through wire 130, closed switch 128, wire 131, switch 177, and wires 178, 179 and 180 to actuate the reset solenoids in both totalizer units. The armature 260 of reset solenoid 61, for example, rotates ratchet wheel 261, fixed on shaft B, in the reverse direction in step by step movement, until all the lights in monogram sections 34 and 35 are extinguished and all three cams 71, 72 and 73 have been turned back to their zero positions, as illustrated in Figure 3. When this condition is accomplished, it will be observed that the various switches operated by these cams are returned to their open circuit positions, as illustrated. When switches 242, 245 and 247 are all reopened, the circuit is broken between supply wire 250 and wire 125, deenergizing reset relay 53, stopping motor 57 by the open-

ing of switch 126, and returning the whole system to its original condition.

Having now described our invention and in what manner the same may be used, what we claim as new and desire to protect by Letters Patent is:

1. Scoring apparatus for a boxing match and the like having a plurality of judging officials comprising an individual scoring device for each judging official, selector means in each of said scoring devices having a plurality of positions in a first range to award different numbers of points to one contestant and a plurality of positions in a second range to award different numbers of points to the other contestant, a score board, an individual number display section on said score board for each judging official, each of said individual display sections having one portion to indicate the number of points awarded to one contestant in one round of the match and another portion to indicate the number of points awarded to the other contestant in one round of the match, a number display section on said score board to indicate the total number of points awarded to each contestant in all the completed rounds, and means for adding the numbers indicated in the corresponding portions of said judging officials' display sections after each round to numbers in the respective display sections for the two contestants.

2. In a boxing score board and the like, a plurality of scoring boxes, an individual number display section controlled by each of said scoring boxes, means requiring the operation of all of said scoring boxes to operate all of said individual display sections simultaneously as soon as all the scoring boxes have been operated, a totalizer unit for each contestant, cumulative total display sections for the contestants operated by the respective totalizer units to increase the total number of points for each contestant by the number of additional points transmitted to said individual display sections by said scoring boxes, the operation of said individual display sections and totalizer units being initiated by the last of said plurality of scoring boxes to be operated in each round, a round number indicating display section, and a timekeeper's control box having a single means to change the number of the round and remove the numbers displayed in all of said individual number display sections.

3. In a boxing score board and the like, individual number display sections for a plurality of judging officials, a cumulative total display section for each contestant, an individual scoring box for each judging official, means in said scoring boxes for selecting numbers to be displayed in the respective individual display sections, counting and totalizing means for adding points awarded to each contestant by said scoring box means to the numbers in said cumulative display sections, means requiring the operation of all of said scoring boxes for simultaneously operating all of said individual number display sections and for initiating the operation of said counting and totalizing means, a round number display section, a timekeeper's control box, and a common means in said timekeeper's control box for simultaneously changing the round number and removing the numbers displayed in said individual number display sections.

4. In a boxing score board and the like, totalizing units for two contestants, means for imparting step-by-step movement to said totalizing units, a first series of contacts engaged by a rotary

switch arm for imparting a number of impulses to one of said totalizing units according to the number of contacts in said first series which are energized, a second series of contacts engaged by said switch arm to impart a series of impulses to the other totalizing unit according to the number of contacts which are energized in said second series, a plurality of scoring boxes each having a selector switch with a first range of positions to award different numbers of points to one contestant and a second range of positions to award different numbers of points to the other contestant, contacts in each scoring box in said first range of positions each contact being connected to energize a different number of contacts in said first series of contacts, contacts in each scoring box in said second range of positions each contact being connected to energize a different number of contacts in said second series of contacts engaged by said rotating switch arm, one revolution of said switch arm actuating both of said totalizer units to add together all the points awarded to each contestant on all the scoring boxes.

5. Scoring apparatus for a boxing match and the like having a plurality of judging officials comprising an individual scoring device for each judging official, selector means in each of said scoring devices having a plurality of positions in a first range to award different numbers of points to one contestant and a plurality of positions in a second range to award different numbers of points to the other contestant, a score board, an individual number display section on said score board for each judging official, each of said individual display sections having available in one portion a plurality of numbers to indicate points awarded to one contestant in one round of the match and having available in another portion a plurality of numbers to indicate points awarded to the other contestant in the same round, a cumulative total display section for each contestant, a totalizer unit for each contestant controlling said last display sections, respectively, and means requiring the operation of all of said scoring devices to transmit the numbers of points awarded in said selector devices to said individual number display sections and said totalizer units when all the scoring devices have been operated.

6. Scoring apparatus for a boxing match and the like having a plurality of judging officials comprising an individual scoring device for each judging official, selector means in each of said scoring devices having a plurality of positions in a first range to award different numbers of points to one contestant and a plurality of positions in a second range to award different numbers of points to the other contestant, a score board, an individual number display section on said score board for each judging official, each of said individual display sections having available in one portion a plurality of numbers to indicate points awarded to one contestant in one round of the match and having available in another portion a plurality of numbers to indicate points awarded to the other contestant in the same round, a

cumulative total display section for each contestant, a totalizer unit for each contestant controlling said last display sections, respectively, means requiring the operation of all of said scoring devices to transmit the numbers of points awarded in said selector devices to said individual number display sections and said totalizer units when all the scoring devices have been operated, a display section on said score board to indicate the number of the round, a timekeeper's control device, and a manipulable member in said timekeeper's control device to change the number of the round and remove the numbers displayed in said individual judge's display sections.

- 15 7. Scoring apparatus for a boxing match and the like having a plurality of judging officials comprising an individual scoring device for each judging official, selector means in each of said scoring devices having a plurality of positions in a first range to award different numbers of points to one contestant and a plurality of positions in a second range to award different numbers of points to the other contestant, a score board, an individual number display section on said score board for each judging official, each of said individual display sections having available in one portion a plurality of numbers to indicate points awarded to one contestant in one round of the match and having available in another portion a plurality of numbers to indicate points awarded to the other contestant in the same round, a cumulative total display section for each contestant, a display section to indicate the number of the round, means for transmitting the numbers of points awarded to the contestants on said scoring devices to the respective judge's display sections, means for adding the numbers of points awarded by all the judges to the respective cumulative total display sections for each contestant, means requiring the operation of all of said scoring devices to initiate the operation of said transmitting means and adding means, and a timekeeper's control device operable to change the number of the round and remove the numbers displayed in said judge's display sections.
